DESIGN FOR A VEHICLE BODY

David Ruttner, Binghamton, N. Y.

Application September 3, 1938, Serial No. 79,741

Term of patent 14 years

To all whom it may concern:

Be it known that I, David Ruttner, a citizen of the United States, residing at Binghamton, in the county of Broome and State of New York, have invented a new, original, and ornamental Design for a Vehicle Body, of which the following is a specification, reference being had to the accompanying drawing, constituting a part thereof.

Figure 1 of the drawing is a side elevational view of a vehicle body showing my new design.

Figure 2 of the drawing is a perspective view of the vehicle body shown in Figure 1.

The design illustrated on the side panel of the vehicle body is painted and the other side of the vehicle body is the same as shown. The rear portion of the vehicle body is conventional.

I claim:

The ornamental design for a vehicle body, substantially as shown and described.

DAVID RUTTNER,
